UNITED STATES PATENT OFFICE.

JOHN J. CAMPBELL, OF LA FAYETTE, INDIANA.

IMPROVEMENT IN DITCHERS AND TILE-LAYERS.

Specification forming part of Letters Patent No. 178,231, dated June 6, 1876; application filed January 21, 1876.

To all whom it may concern:

Be it known that I, JOHN J. CAMPBELL, of La Fayette, in the county of Tippecanoe and State of Indiana, have invented a new and useful Improved Ditcher and Tile-Layer, of which the following is a specification:

The object of this invention is to open draining-ditches, and at the same time lay drain-tiles, or deposit gravel in the drain, through which the water will flow.

In the annexed drawings, which make a part of this specification, Figure 1 is a perspective view of the entire machine. Fig. 2 is a sectional elevation, and Fig. 3 shows a section taken from the vertical bar which carries the plows and tile or gravel box.

The same letters in all the figures indicate identical parts.

A is the draft-beam, to which the chain or cable is fastened, by which the machine is drawn through the earth by means of a capstan. To the rear end of this is fastened the vertical beam B, which carries the plows. It is made sharp in front to open the earth, and may be faced with steel plates. Threaded rods D D are screwed through the beam A, and into iron nuts on the cross-bars of the shoe C, which slides on the surface of the ground, and is adjusted by the screws D to regulate the depth of the cut. On the lower end of the cutter-beam B is a triangular plow E, pointed in front, and having the share E' on the bottom to smooth the bottom of the drain. Other plows, F F—one or more of them—of similar shape, are secured to the cutter-beam, and, preferably, inclined downward at the point, for the purpose of loosening the earth. In the recess B', in the rear side of the cutter-beam, the shaft G is secured by stepping its lower end in the plow E, and at the top by a strap, K. This shaft carries the tile or gravel box, which is composed of steel plates G¹ G² G³, forming distinct sections, of which more or less may be employed, according to the depth of the cut. Through the box is an opening, G¹, opening at the top and through the lower rear angle of the box. Wooden blocks G³ are placed in the front end of the box, between the respective plates forming the sections. An apron, H, of spring-steel, is placed in the opening G¹, and, being secured

at the upper end to the wooden block, extends downward, and is curved at the lower end to rest flat upon the bottom of the drain. A block, I, is hung by side straps at the rear end of the upper section of the box. It is flared at the top on the sides. The object of this block is to prevent the caving in of the earth so as to interfere with the proper deposition of the tile or gravel. On the draft-beam A is a spirit-level, L, which is fastened by a set-screw to the upper edge of a hinged plate, L¹, pivoted to the draft-beam. The position of the plate is determined by the eccentric L², pivoted to the draft-beam below the plate L¹. An index-finger, L³, indicates the angle of inclination on a graduate scale marked on the plate L¹.

The operation of the machine is as follows: The depth of cut having been determined, the shoe C is regulated at the proper distance above the plow E, and the box is formed of the required number of sections to bring the apron H upon the level of the share E and the top of the block G I, with its flanges upon the surface of the ground. The plate L¹ should also be adjusted so that the level will indicate by its bubble when the machine is cutting either horizontally or at a required inclination to give the prescribed inclination to the bottom of the drain. When properly arranged, the machine is drawn through the earth by the cable and capstan, and the tile are fed into the box at G¹ continuously, and deposited in the drain. Gravel may be fed in to fill the channel cut by the plow E. In either case the block I will keep the cut open until the sections of tile or the gravel have been deposited.

I am aware that a beam carrying the plow, and supported on a sled or shoe, and fitted with adjusting-screws to fix the inclination of the mole-plow, have been used. My invention differs from them in the respect that I dispense with the draft-rods which in that machine connect the shoe and plow-standard, and employ a light shoe, which has only to sustain the weight of the beam and its own friction. My claim will, therefore, be limited to combinations in which the beam performs its function of a draft-beam, transmitting the draft directly to the ditching mechanism without the intervention of intermediate parts.

What I claim as my invention, and desire to secure by Letters Patent, is—

1. In combination with the draft beam A and cutter-beam B, the plow E, carrying on its lower face the share E', for finishing the bottom of the drain, substantially as set forth.

2. In combination with the solid cutter-beam B, opening the ditch by forcing the earth to each side, and drain-plow E, one or more auxiliary plows, F, arranged above the latter to loosen the earth, substantially as set forth.

3. The tile or gravel box, constructed in sec-

tions, made adjustable to conform to the depth of the cut, substantially as set forth.

4. In combination with the tile or gravel box, the flaring block I, for keeping the earth from caving in until the tile or gravel has been deposited behind the apron H, substantially as set forth.

In testimony whereof I have signed my name to this specification in the presence of two subscribing witnesses.

JOHN J. CAMPBELL.
